PAUL C. SAINSEVAIN, OF SAN JOSE, CALIFORNIA, ASSIGNOR OF ONE-HALF
TO ALPHONSE G. COL, OF SAN JOSE, CALIFORNIA.

ROTARY EXPLOSIVE-ENGINE.

SPECIFICATION forming part of Letters Patent No. 726,353, dated April 28, 1903.

Application filed June 12, 1902. Serial No. 111,265. (No model.)

To all whom it may concern:

Be it known that I, PAUL CHARLES SAINSEVAIN, a citizen of the United States, residing at San Jose, in the county of Santa Clara and State of California, have invented certain new and useful Improvements in Rotary Explosive-Engines, of which the following is a specification.

My invention relates to rotary explosive-engines, the object of my invention being to provide an engine of this character which shall be simple in construction and of great efficiency in proportion to the size of the engine.

My invention therefore resides in the novel construction, combination, and arrangement of parts for the above ends hereinafter fully specified, and particularly pointed out in the claims.

In the accompanying drawings, Figure 1 is a vertical longitudinal section of my improved rotary engine. Fig. 2 is a horizontal section thereof. Fig. 3 is a vertical section on the line A-A of Fig. 1 looking in the direction of the arrow. Fig. 4 is a vertical section on the line B-B of Fig. 1 looking in the direction of the arrow. Fig. 5 is a broken vertical section through the cylinder on the line C-C of Fig. 1 looking in the direction of the arrow.

Fig. 6 is a similar section on the line D-D of Fig. 1 looking in the same direction. Fig. 7 is a perspective view of the shaft and the oscillating piston detached. Fig. 8 is a similar view of the fixed piston detached. Fig. 9 is a view of an end of the machine on the left-hand side of Fig. 1. Fig. 10 is a vertical section of the engine on the line E-E of Fig. 1. Fig. 11 is an enlarged detail end view showing the sparking mechanism in front elevation. Fig. 12 is a view of a portion of the sparking mechanism on the inside of the cylinder. Fig. 13 is a section on the line F-F of Fig. 11.

Referring to the drawings, 1 represents the shaft of my improved rotary explosive-engine mounted in pillow-blocks 2, supported on suitable standards 3. Said shaft is hollow for the greater portion of its length, as shown, its ends being closed by the plugs 4, upon which are secured gear-wheels 5 for conveying the power generated by the engine to any suitable ma-

chinery wherein it is desired to utilize the same. Upon said shaft 1 is mounted the rotary cylinder 7, the cylinder-heads 8 whereof are secured in place upon the shaft 1 by means of the nuts 9. To said cylinder is secured the fixed piston 10, which passes through a longitudinal slot or aperture 11 in the hollow shaft, fitting snugly in said aperture. Thereby the cylinder is secured to said shaft and transmits rotation thereto. The fixed piston is cut out or reduced in width in its central portion, as shown at 12, so that while the middle portion of the shaft is completely closed by said central portion of the piston against the passage of gases from one end of said shaft to the other there is left at each end of the hollow shaft within the cylinder an opening or port 13, by means of which the gases pass between said hollow shaft and the interior of the cylinder. To permit this to be done, the fixed piston is recessed, as shown at 14, in its opposite faces, said recesses being in the two halves thereof which extend on opposite sides of the shaft. The recess 14 in each face is extended inward or toward the shaft at one corner in proximity to the head of the cylinder, so as to communicate with the port 13 in the shaft, so that while said extension 15 on one face communicates with the steam-port at one end of the cylinder the extension 15 from the other recess communicates with the port at the other end of the cylinder, as clearly shown by comparison of Figs. 5 and 6. Upon the shaft 1 is also rotatably mounted the oscillating piston 16. Said oscillating piston comprises hub portions 17, which revolve in annular recesses 18 in the cylinder-heads, bridges 19 connecting said hub portions and wings 20 extending from said bridges. Said wings 20 have depressions on alternately opposite faces thereof and within said depressions are formed shields 21. Said hubs, bridges, wings, and shields are all formed in a single casting. The bridges are concaved on their under sides to conform to the cylindrical surface of the shaft and have suitable packings 22 secured in said under sides. The two sides of each wing are connected within the shield by a rod 23, upon which is pivotally mounted a link 24, connected to crank-arms 25 upon shafts 26, ex-

tending through suitable boxes 27 in the cylinder-head and having mounted on their ends gear-wheels 28, which revolve around and mesh with stationary gear-wheels 29, secured upon the pillow-blocks. By this means as the cylinder revolves the gear-wheels 28 revolve around the fixed gear-wheels 29 and impart an epicycloidal motion to the crank-arms. The diameter of the gear-wheel 29 is twice that of the gear-wheels 28. The oscillating piston, therefore, in one revolution of the cylinder makes two complete oscillations to and from the fixed piston. In one of these oscillations the gas is ignited, exploded, and discharged, and in the second oscillation a fresh supply of gas and air is drawn into the exploding-chamber and is compressed ready for the next explosion.

The explosive mixture of gas and air is admitted from a supply-pipe 30 at each end of the engine through a port 31 in the pillow-block, and the products of explosion are also discharged through a port 32 in said pillow-block. The ports 31 and 32 at one end of the engine are used for communicating with one of the explosive-chambers 33 between the oscillating and fixed pistons, while the ports 31 and 32 at the other end of the engine are used for communicating with the other of said explosive-chambers 33. To accomplish this there are provided in the ends of the hollow shaft ports 34, communicating with said supply and discharge ports 31 and 32 alternately in the revolution of the shaft. In order to insure that the explosions in the two explosive-chambers shall take place alternately—that is to say, that the gas shall be exploded and discharged into one chamber while at the same time a fresh supply of gas is being drawn in and compressed in the other chamber—I arrange the two ports 34 in the circumference of the hollow shaft on diametrically opposite sides of said shaft. Thus supposing that the cylinder is revolving in the direction of the arrow shown in Fig. 10 and the lower explosion-chamber 33 has arrived at such a position that explosion takes place therein, the opposite explosion-chamber will at the same time have come into communication, by means of the extended recess 15, the port 13, the port 34, and the supply-port 31, with the supply-pipe 30, so that at the same moment that explosion takes place in the lower explosion-chamber a charge of the explosion mixture begins to enter the upper explosion-chamber. The upper explosion-chamber in Fig. 10 is connected by means of the extended recess 15 with the ports at the end of the engine on the left in Fig. 1, while the explosion-chamber on the right is connected with those on the right of Fig. 1. In order, therefore, for the explosive mixture to be drawn into the upper explosion-chamber at the same time that the explosion takes place in the lower explosion-chamber the port 34 in the shaft must be just beginning to pass the inlet-port from the supply-pipe 30. The port 34 in the shaft at the

left-hand side of Fig. 1 is therefore in its uppermost position. At the same time the corresponding port at the right-hand side of Fig. 1 is in its lowermost position and is shut off from both the supply and exhaust ports in the pillow-block. When the shaft has turned through one-quarter of a revolution so that the crank-shafts 26 have moved through one-half of a revolution, the port 34 on the right-hand side of Fig. 1 will have moved to such a position as to communicate with the exhaust-port at that end of the engine, and the products of explosion will be exhausted from the right-hand explosion-chamber 33 of Fig. 10. At the same time the left-hand explosion-chamber of Fig. 10 will now be cut off from the supply-pipe, the port 34 having just passed the supply-port, and upon the return of the oscillating piston toward the fixed piston the explosion-chamber on the left-hand side of Fig. 10 will begin to contract, thus compressing the explosive mixture therein. This contraction will take place until the parts have again arrived at the position shown in Fig. 10, when an explosion will take place in the explosion-chamber in which the explosive mixture has been compressed, and the operation will be repeated continuously, there being two explosions for each revolution of the shaft—namely, one explosion in each explosion-chamber. It will thus be seen that I provide in a rotary engine the four-cycle operations of charging, compressing, exploding, and exhausting.

For obtaining the spark I provide the following construction: Through the cylinder-head is inserted a tube 40, within which is an asbestos packing 41 around an electrode 42. At a proper point in the revolution of the shaft the end 43 of the electrode which projects outside the cylinder-head comes into contact with a spring contact-plate 44, supported on a suitable bracket 45 from one of the standards and insulated as shown at 46. The two wires 47 48 from the spark-coil 49 are connected the one, 47, with the spring-contact 44 and the other, 48, through the standard with the cylinder-head. In said cylinder-head is also mounted a shaft 50, carrying on its inner end a hammer 51, which is normally pressed against the inner end 52 of the electrode 42 by means of a spring 53, which is attached to an arm 54 on the outer end of the shaft. Thus as soon as the outer end 43 of the electrode touches the contact-plate a circuit is made through the wire 47, contact-plate 44, electrode 42, hammer 51, cylinder-head 8, standard 3, and wire 48, around the coil. Said contact-plate carries a finger 55, insulated therefrom by suitable insulation 56, which at a proper point in the revolution of the shaft engages a lever 57 on the shaft 50, and thereby throws the hammer 51 off from contact with the inner end of the electrode 42, making the spark and causing an explosion in the mixture of gas and air. There is one such hammer for each of the explosion-

chambers, so that an explosion takes place in each chamber in turn as it comes to the sparking device.

It is evident that the principles of my invention and many details of the construction thereof may be used in a rotary steam-engine as well as in a rotary explosive-engine, and I do not desire my invention to be limited to the latter.

10 I claim—

1. In a rotary engine, the combination of a revolving cylinder, a piston revolving therewith, a second piston oscillating to and from the first piston, a shaft extending through a cylinder-head and connected with the oscillating piston, a gear-wheel on said shaft, a fixed gear-wheel about which said gear-wheel revolves, and means for admitting pressure fluid into a chamber between the pistons and 15 exhausting it therefrom, substantially as described.

2. In a rotary engine, the combination of a revolving cylinder, a piston revolving therewith, a second piston oscillating to and from the first piston, shafts extending through the cylinder-heads, gear-wheels on said shafts, fixed gear-wheels about which said gear-wheels revolve, and means for admitting pressure fluid to a chamber between the pistons and 20 exhausting it therefrom, substantially as described.

3. In a rotary engine, the combination of a revolving cylinder, a piston revolving therewith, a piston oscillating relatively to the revolving piston, means actuated by the revolution of the cylinder for imparting said oscillating movement to said piston, said means extending through the cylinder-head, and means for admitting pressure fluid to a chamber 25 between the two pistons and exhausting it therefrom, substantially as described.

4. In a rotary engine, the combination of a revolving cylinder, a hollow shaft therefor, a fixed piston extending through said hollow shaft and connected with said cylinder, a piston oscillating about said shaft to and from the fixed piston, and means for conducting pressure fluid through said hollow shaft to and from a chamber between the fixed and oscillating pistons, substantially as described.

5. In a rotary engine, the combination of a revolving cylinder, a hollow shaft, a fixed piston secured to said shaft and to the cylinder, an oscillating piston the sides of which move 55 in contact with the cylinder-heads to and from the fixed piston, said oscillating piston

having an annular hub and said heads having an annular groove in which said hub moves, and means for conducting pressure fluid through said shaft to and from a pressure-chamber between the fixed and oscillating pistons, substantially as described.

6. In a rotary engine, the combination of a revolving cylinder, a hollow shaft, a fixed piston rotating with said shaft and with the cylinder, an oscillating piston having a hub revolving upon said shaft, and having wings extending from said hub between the cylinder-heads, said wings having shields, shafts between the sides of the wings in said shields, 60 shafts through the cylinder-heads having crank-arms with the shafts between the wings, gear-wheels on the shafts extending through the cylinder-heads, fixed gear-wheels about which the former gear-wheels rotate, 65 and means for conveying pressure fluid through said hollow shaft to and from a pressure-chamber between the fixed and oscillating pistons, substantially as described.

7. In a rotary engine, the combination of a revolving cylinder, a hollow shaft closed at its central portion, a piston revolving with said shaft and cylinder, an oscillating piston on said shaft forming two pressure-chambers with said fixed piston, individual passages 80 from the ends of said hollow shaft to the pressure-chambers, and valves controlling the admission and exhaust of pressure fluid to and from the ends of said hollow shaft, substantially as described.

8. In a rotary engine, the combination of a revolving cylinder, a shaft, a fixed piston rotating with said shaft and cylinder, an oscillating piston rotating on said shaft, means for imparting two complete oscillations to said 85 piston in one revolution of the shaft and cylinder, valves and passages to the chambers between the oscillating and fixed pistons, and a sparking device, said valves, passages and 90 sparking device being arranged to explode and discharge the explosive mixture in one of said complete oscillations and to admit and compress a charge of the explosive mixture in the second oscillation, substantially as described.

105 In witness whereof I have hereunto set my hand in the presence of two subscribing witnesses.

PAUL C. SAINSEVAIN.
